UNITED STATES PATENT OFFICE.

EDWARD H. GIBSON AND ABRAM D. BEVIER, OF CLYDE, OHIO.

ROLLER WINDOW-SCREEN.

933,245.

Specification of Letters Patent.

Patented Sept. 7, 1909.

Application filed March 2, 1909. Serial No. 480,933.

To all whom it may concern:

Be it known that we, EDWARD H. GIBSON and ABRAM D. BEVIER, citizens of the United States, and residents of Clyde, in the county 5 of Sandusky and State of Ohio, have invented certain new and useful Improvements in Roller Window-Screens, of which the following is a specification.

Our invention relates to window-screens, 10 and has for its object the provision of a screen having one edge mounted on a roller journaled in a suitable boxing and its opposite edge secured to the window-sill under the lower sash, said boxing having the width 15 of the window-sash, and slidably mounted in the channel in the frame in which the sash is mounted. A metal tape is secured to each end of the roller and arranged to wind on the ends of the roller as the boxing is lifted, 20 so as to hold the boxing in an adjusted position when raised, and when the boxing is lowered the tapes unwinding from the roller serve to rotate it to wrap the screen thereon. The free ends of the tapes are secured to 25 springs at the top of the frame that hold the tapes taut at all times to compensate for the difference in thickness in the screen and tape on the roller.

The construction and operation of our 30 improved window-screen will be described in detail hereinafter and illustrated in the accompanying drawings, in which—

Figure 1 is a view of a window, showing our improved screen therein; Fig. 2, a cross- 35 section, showing the lower end of the frame and sash and screen; Fig. 3, a detail view of the box and tapes; and Fig. 4, a detail view, showing the roller removed from the box and tapes in position.

40 In the drawings similar reference characters indicate corresponding parts in all of the views.

The window frame or casing A is constructed in the usual manner and is provided 45 with the beads B and C, forming the channels for the sash D.

Our improvement consists of a boxing or housing 1, slidably mounted in the channel under the lower sash D, in which box is journaled a roller 2, having a length of wire- 50 screen fabric 3 secured at one edge thereto, while its other edge is bent at an angle, as shown at 4, and secured to the window-sill E by any suitable fastenings 5.

Secured to the ends of roller 2 are tapes 55 6, made preferably of metal and arranged to wind on the roller in the contrary direction to the screen-fabric. The tapes 6 are extended through openings 7 in the ends of the boxing or housing 1 and up the frame 60 between the front of the lower sash D and bead C, the upper ends of the tapes being secured to the free ends of leaf-springs 8, secured to the top of the frame A.

It will be understood that when the device 65 is in position, as shown, the sash D may be raised independently of the screen, or, if desired, the housing 1 and sash may be raised simultaneously, unrolling the screen so as to cover the opening, or when the sash is 70 raised the housing may be raised or lowered to screen the opening. When the housing is raised, it will be apparent that the tapes 6 will be wound on the ends of the roller, so that in whatever position the housing is 75 brought to rest it will be held in position, and when lowered the tapes by unwinding from the roller will rotate it and wind the screen thereon, the springs 8 by holding the tapes taut at all times serving to retain the 80 screen stretched and, as stated, compensating for the differences in thicknesses of the screen and tapes wound upon the roller.

Having thus described our invention, 85 what we claim is—

In combination with a window casing having a sill, and window-sashes mounted in said casing, a housing slidably mounted in said casing under the lower sash and independently thereof, a roller journaled 90 in the housing, a screen secured to the roller and to the sill, tapes secured to the roller and arranged to wind thereon in a contrary direction to the screen, and leaf springs secured to the top of the window-casing and 95 engaging the free ends of the tapes to hold them taut, substantially as shown and described.

In witness whereof, we have hereunto set our hands in presence of two subscribing 100 witnesses.

EDWARD H. GIBSON.
ABRAM D. BEVIER.
